UNITED STATES PATENT OFFICE.

FERDINAND WESEL, OF NEW YORK, N. Y.

STEREOTYPE-PLATE HOLDER.

SPECIFICATION forming part of Letters Patent No. 276,204, dated April 24, 1883.

Application filed November 14, 1882. (No model.)

To all whom it may concern:

Be it known that I, FERDINAND WESEL, of New York, in the county and State of New York, have invented an Improved Stereotype-Plate Holder, of which the following is a specification.

Figure 1 is a top view of my improved stereotype-block; Fig. 2, a vertical section thereof on the line *c c*, Fig. 1; Fig. 3, a vertical section on the line *ck*, Fig. 1; Fig. 4, a side view, and Fig. 5 an end view, of one of the spacing-plugs employed in the block. Fig. 6 is a perspective view, and Fig. 7 a top view, of one of the plate-holding jaws.

15 In the drawings, the letter A represents my improved block. The same has series of grooves *a a* extending diagonally across its face, all parallel with one another. In cross-section the grooves may be of the form of inverted letters *T*, as shown in Fig. 2, or of dovetail or other analogous form.

20 B B are the jaws for clamping the stereotype-plates C C. The shank *b* of each jaw B is intended to enter and fit, and therefore has the form of, the groove *a*, as indicated in Figs. 2 and 6. The plate-holding upper part, *d*, of the jaw has a beveled or inclined holding-face, which is to bear against the bevel edge of the plate C, as shown in Fig. 3.

In each end of each groove *a* is hung a screw-spindle, D, parallel with the groove. On this screw travels a nut, E.

F F are spacing-plugs to be inserted between the nuts E and jaws B. When a plate, C, has been placed in its proper location upon the block A, four or more jaws, B B, are brought to bear against its edges, and are then tightened by turning the screws D and crowding the nuts E and interposed plugs F against said jaws. Plugs of varying lengths must be on hand to permit of the proper locking of the plates. In each jaw the shank *b* must be diagonal to the biting-edge of the top part, *d*, as shown.

I claim—

1. The block A, having diagonal grooves *a a*, in combination with the diagonal screws D and their nuts E, substantially as herein shown and described.

2. The block A, having diagonal grooves *a a*, in combination with screws D, nuts E, and jaws B, substantially as herein shown and described.

FERDINAND WESEL.
